UNITED STATES PATENT OFFICE

EDWARD LESLIE HELWIG, OF BRISTOL TOWNSHIP, BUCKS COUNTY, PENNSYLVANIA

PROCESS FOR THE PRODUCTION OF THIOCYANO DERIVATIVES

No Drawing.

Application filed October 3, 1929. Serial No. 397,163.

This invention relates to the production of the thiocyanato derivatives of aromatic compounds.

In the past it has been customary to prepare thiocyanato derivatives by the action of a halogen on a mixture of an alkali thiocyanate and the compound whose thiocyanato derivative was to be prepared. This method is open to many serious objections. It is usually necessary to carry on this reaction at a very low temperature and in the absence of water in order to get an appreciable yield. With the cheaper halogen, chlorine, the yield is usually poor due to the many side reactions which take place. Some chlorination takes place and also considerable oxidation of the thiocyanato derivative to a disulphide derivative. Also, the presence of free halogen tends to accelerate the polymerization of thiocyanogen. With the more expensive halogens, bromine and iodine, the yield is considerably better but the recovery of the halogens is not easy and thus the process becomes quite expensive.

These derivatives have also been prepared by the action of thiocyanogen on the compound in an inert solvent. This is also not very satisfactory due to the rapid polymerization of the thiocyanogen.

I have found that these thiocyanato derivatives can be very conveniently prepared in good yields electrolytically. The compound whose thiocyanato derivative is to be prepared, sometimes known as the depolarizer, is mixed with a soluble thiocyanate or thiocyanic acid and electrolyzed, using an insoluble anode.

It is usually not necessary to use a diaphragm although it is advisable where the compound desired is easily reducible.

Cooling the electrolyte has been found to increase the yield.

In most cases, alcohol has been added to the electrolyte to increase the solubility of the compound whose thiocyanato derivative is to be prepared, and in some cases to prevent freezing at the low temperatures employed.

The current density is so regulated that the thiocyanogen is liberated only so rap-

idly as it can be taken up by the compound, whose thiocyanato derivative is to be prepared, as otherwise it is wasted either by further oxidation or by polymerization. In the absence of said compound the bulk of the thiocyanogen polymerizes as it is liberated*. As the concentration of the said compound drops off towards the end of the reaction, it is frequently advisable to reduce the current density somewhat to prevent wasting thiocyanate.

It is not necessary to restrict the work to any particular anode material, the only qualifications being that the electrode must not oxidize the thiocyanogen or the compound used too far nor be attacked itself. Any cathode material may be used which will not reduce the desired thiocyanato derivative, and even this restriction is removed if a diaphragm is employed.

I have obtained the best results when applying my invention to the production of para-thiocyanato derivatives, although it may be adapted to the production of meta and ortho derivatives.

The following examples will serve to illustrate the nature of the invention but the invention is not restricted to the examples.

The proportions are by weight.

Example 1. The preparation of para-thiocyanato-ortho-toluidine

The following electrolyte is made up: 20 parts sodium thiocyanate, 35 parts water, 25 parts hydrochloric acid (35%), 25 parts ethyl alcohol (95%), 12 parts ortho-toluidine. This is electrolyzed between a rotating graphite anode and a copper cathode. The cell is cooled to 0° C. + 5° C. The anode current density is maintained at about 2 amperes per square decimeter. When 1.25 times the theoretical amount of current, measured as ampere hours or any other units, has passed through the cell, the current is interrupted. The electrolyte is found to contain a yield of 75% of the product, based on the toluidine taken, showing a current efficiency of 60%.

Example 2. The preparation of para-thiocyanato-dimethylaniline

The following electrolyte is made up:

5 37 parts ammonium thiocyanate, 95 parts water, 50 parts ethyl alcohol (95%), 43 parts dimethylaniline, 38 parts hydrochloric acid (35%). The electrolyte is cooled to 0° C. and, while being circulated by means of a centrifugal pump, is electrolyzed between stationary graphite anodes and copper cathodes. An anode current density of 2 to 3 amperes per square decimeter is maintained and 1.2 to 1.4 times the theoretical amount of current is passed through the cell.

10 15 75% of the dimethylaniline is converted to the thiocyanato derivative.

Example 3. The preparation of 2-amino 5-thiocyanato benzoic acid

20 The following electrolyte is made up: 20 parts sodium thiocyanate, 17 parts water, 21 parts hydrochloric acid (35%), 35 parts methyl alcohol, 14 parts anthranilic acid. This is electrolyzed between a rotating graphite anode and a stationary aluminum cathode, using an anode current density of 1.0 to 1.5 amperes per square decimeter, the temperature being maintained around +5° C. 1.5 times the theoretical amount of current is used. 60% of the anthranilic acid is converted to the thiocyanato derivative.

Example 4. The preparation of 1-amino 4-thiocyanato naphthalene

35 34 parts of a 76% solution of calcium thiocyanate are treated with 60 parts of 20% sulphuric acid in the cold. The calcium sulphate so formed is filtered off and 40 washed with 35 parts methyl alcohol. To the filtrate and washings, 15 parts alpha-naphthylamine are added. The electrolyte is cooled to 0° C. and electrolyzed between a rotating graphite anode and an aluminum cathode; a current density of 1.5 amperes per square decimeter being maintained. Twice the theoretical current is passed through the cell. A yield of 50%–55% is obtained, based on the alpha-naphthylamine taken.

Example 5. The preparation of para-thiocyanato-ortho-cresol

The following electrolyte is made up:

55 20 parts sodium thiocyanate, 27 parts water, 25 parts hydrochloric acid (35%), 36 parts methyl alcohol, 11 parts ortho cresol. This is electrolyzed between a rotating graphite anode and an aluminum cathode, using a current density of 2 amperes per square decimeter, until 1.5 times the theoretical current is passed. The temperature is maintained at -5° C. A yield of approximately 40% is obtained, based 60 65 on the cresol taken.

Example 6. Thiocyanato resorcinol

25 parts calcium thiocyanate solution 70% are treated with 63 parts sulphuric acid 20% and the calcium sulphate filtered off. 70 The cake is washed with 25 parts ethyl alcohol 95%. To the filtrate and washings are added 12 parts resorcinol. This solution is electrolyzed between a rotating graphite anode and a copper cathode, using an anode current density of 1.5 amperes per square decimeter at 0° C. until the theoretical amount of current has passed through the cell. A yield of 60% thiocyanato-resorcinol is obtained, based on the resorcinol taken. 75 80

Example 7. Thiocyanato resorcinol

12 parts resorcinol and 20 parts sodium thiocyanate are dissolved in 60 parts water. This solution is placed in the anode compartment of a divided cell. 5% sodium hydroxide solution is placed in the cathode compartment. A rotating graphite anode and copper cathode are used. An anode current density of 1 to 2 amperes per square decimeter is maintained until the theoretical amount of current has been used. The anolyte then contains 50–60% of the theoretical amount of thiocyanato-resorcinol. 85 90

Example 8. Thiocyanato phenol

14 parts of 88% phenol and 20 parts sodium thiocyanate are dissolved in 15 parts of ethyl alcohol and 35 parts water. This solution is placed in the anode compartment of a divided cell. 10% sodium hydroxide solution is placed in the cathode compartment. A rotating graphite anode and copper cathode are used. An anode current density of 1 ampere per square decimeter is maintained until the theoretical amount of current has been used. The temperature is kept between 0° C. and 13° C. At the end of the electrolysis, the anolyte is found to contain 25% of the theoretical amount of thiocyanato phenol. 100 105 110

Having thus described the nature and objects of my invention and illustrated specific embodiments of the same, what I claim as new and desire to secure by Letters Patent is:

1. A process for the production of thiocyanato derivatives of organic compounds which comprises mixing the compound whose derivative is desired with a substance capable of yielding thiocyanogen ions and electrolyzing the mixture. 120

2. A process for the production of thiocyanato derivatives of aromatic compounds which comprises mixing the compound whose derivative is desired with a substance capable of yielding thiocyanogen ions and electrolyzing the mixture. 125

3. A process for the production of para-thiocyanato derivatives of aromatic com- 130

- pounds which comprises mixing the compound whose derivative is desired with a substance capable of yielding thiocyanogen ions and electrolyzing the mixture.
4. A process for the production of the thiocyanato derivatives of an aromatic compound of the group consisting of amines and phenols which comprises mixing the compound whose derivative is desired with a substance capable of yielding thiocyanogen ions and electrolyzing the mixture. 10
5. A process for the production of the para-thiocyanato derivative of a compound of the group consisting of amines and phenols which comprises mixing the compound whose derivative is desired with a substance capable of yielding thiocyanogen ions and electrolyzing the mixture. 15
6. A process for the production of thiocyanato derivatives of organic compounds which comprises mixing the compound whose derivative is desired with a substance selected from the group consisting of thiocyanates, thiocyanic acid and a substance capable of producing thiocyanic acid and electrolyzing the mixture. 20
7. A process for the production of thiocyanato derivatives of aromatic compounds which comprises mixing the compound whose derivative is desired with a substance selected from the group consisting of thiocyanates, thiocyanic acid and a substance capable of producing thiocyanic acid and electrolyzing the mixture. 30
- 35 8. A process for the production of para-thiocyanato derivatives of aromatic compounds which comprises mixing the compound whose derivative is desired with a substance selected from the group consisting of thiocyanates, thiocyanic acid and a substance capable of producing thiocyanic acid and electrolyzing the mixture.
9. A process for the production of thiocyanato derivatives of an aromatic compound of the group consisting of amines and phenols which comprises mixing the compound whose derivative is desired with a substance selected from the group consisting of thiocyanates, thiocyanic acid and a substance capable of producing thiocyanic acid and electrolyzing the mixture. 45
- 50 10. A process for the production of para-thiocyanato derivatives of a compound of the group consisting of amines and phenols which comprises mixing the compound whose derivative is desired with a substance selected from the group consisting of thiocyanates, thiocyanic acid and a substance capable of producing thiocyanic acid and electrolyzing the mixture. 55
11. A process for the production of thiocyanato derivatives of organic compounds which comprises mixing the compound whose derivative is desired with a substance capable of yielding thiocyanogen ions and electrolyzing the mixture at a temperature below about 5° C. 60
12. A process for the production of thiocyanato derivatives of organic compounds which comprises mixing the compound whose derivative is desired with a substance selected from the group consisting of thiocyanates, thiocyanic acid and a substance capable of producing thiocyanic acid and electrolyzing the mixture at a temperature below about 5° C. 70
- 75 13. A process for the production of thiocyanato derivatives of aromatic compounds which comprises mixing the compound whose derivative is desired with a substance capable of yielding thiocyanogen ions and electrolyzing the mixture at a temperature below about 5° C. 80
- 85 14. A process for the production of para-thiocyanato derivatives of aromatic compounds which comprises mixing the compound whose derivative is desired with a substance capable of yielding thiocyanogen ions and electrolyzing the mixture at a temperature below about 5° C. 90
- 95 15. A process for the production of the thiocyanato derivative of an aromatic compound of the group consisting of amines and phenols which comprises mixing the compound whose derivative is desired with a substance capable of yielding thiocyanogen ions and electrolyzing the mixture at a temperature below about 5° C. 10
16. A process for the production of the para-thiocyanato derivative of a compound of the group consisting of amines and phenols which comprises mixing the compound whose derivative is desired with a substance capable of yielding thiocyanogen ions and electrolyzing the mixture at a temperature below about 5° C. 105
17. A process for the production of thiocyanato derivatives of organic compounds which comprises mixing the compound whose derivative is desired with a substance capable of yielding thiocyanogen ions and an alcohol and electrolyzing the mixture at a temperature below about 5° C. 115
18. A process for the production of para-thiocyanato derivatives of aromatic compounds which comprises mixing the compound whose derivative is desired with a substance capable of yielding thiocyanogen ions and an alcohol and electrolyzing the mixture at a temperature below about 5° C. 125
19. A process for the production of thiocyanato derivatives of organic compounds which comprises mixing the compound whose derivative is desired with a substance capable of yielding thiocyanogen ions and electrolyzing the mixture while maintaining an anode current density between about 1 amp. and 3 amps. per square decimeter of anode surface and while cooling the electrolyte. 130

20. A process for the production of thiocyanogen derivatives of aromatic compounds which comprises mixing the compound whose derivative is desired with a substance capable of yielding thiocyanogen ions and electrolyzing the mixture while maintaining an anode current density of between about 1 amp. and 3 amps. per square decimeter of anode surface and while cooling the electrolyte. 0° C. while maintaining an anode current density of about 1.5 amp. per square decimeter of anode surface. 0
21. A process for the production of the para-thiocyanogen derivative of a compound of the group consisting of amines and phenols which comprises mixing the compound whose derivative is desired with a substance capable of yielding thiocyanogen ions and electrolyzing the mixture while maintaining an anode current density of between about 1 amp. and 3 amps. per square decimeter of anode surface and while cooling the electrolyte. 28. A process for the production of 2-amino, 5-thiocyanogen benzoic acid which comprises mixing anthranilic acid with a substance capable of yielding thiocyanogen ions and electrolyzing the mixture. 70
22. A process for the production of thiocyanogen derivatives of organic compounds which comprises mixing the compound whose derivative is desired with a substance selected from the group consisting of thiocyanates, thiocyanic acid, and a substance capable of producing thiocyanic acid and electrolyzing the mixture while maintaining an anode current density of between about 1 amp. and 3 amps. per square decimeter of anode surface and while cooling the electrolyte. 29. A process for the production of 2-amino, 5-thiocyanogen benzoic acid which comprises mixing anthranilic acid with a thiocyanate and electrolyzing the mixture at a temperature of about 5° C. while maintaining an anode current density of between 1 and 1.5 amps. per square decimeter of anode surface. 75
23. A process for the production of thiocyanogen derivatives of organic compounds which comprises mixing the compound whose derivative is desired with a substance capable of yielding thiocyanogen ions and electrolyzing the mixture at a temperature below about 5° C. while maintaining an anode current density of between about 1 amp. and 3 amps. per square decimeter of anode surface. 80
24. A process for the production of para-thiocyanogen-dimethylaniline which comprises mixing a dimethylaniline salt with a substance capable of yielding thiocyanogen ions and electrolyzing the mixture. 85
25. A process for the production of para-thiocyanogen-dimethylaniline which comprises mixing the hydrochloride of dimethylaniline with ammonium thiocyanate and electrolyzing the mixture at a temperature of about 0° C. while maintaining an anode current density of from 2 to 3 amps. per square decimeter of anode surface. 90
26. A process for the production of thiocyanogen-resorcinol which comprises mixing resorcinol with a substance capable of yielding thiocyanogen ions and electrolyzing the mixture. 95
27. A process for the production of thiocyanogen-resorcinol which comprises mixing resorcinol with thiocyanate and electrolyzing the mixture at a temperature of about 100
- 105
- 110
- 115
- 120
- 125
- 130

In testimony whereof I have hereunto set my hand.

EDWARD LESLIE HELWIG.
